United States Patent

Des. 236,450
Patented Aug. 26, 1975

236,450

PERAMBULATOR

Clarine Johnson, 227 Lenox Ave., Apt. 1,
New York, N.Y. 10027

Filed May 13, 1974, Ser. No. 469,520

Term of patent 14 years

Int. Cl. D12—12

U.S. Cl. D12—128

FIG. 1

FIG. 2

FIG. 3

FIG. 1 is a front perspective view of a perambulator showing my new design;

FIG. 2 is an elevational view of the left side of the perambulator of my design; and

FIG. 3 is an elevational view of the rear of the perambulator of my design.

I claim:

The ornamental design for a perambulator, as shown.
